UNITED STATES PATENT OFFICE.

BENJAMIN KERR, OF SARNIA, ONTARIO, CANADA.

AUTOMOBILE CUSHION.

Application filed December 7, 1923. Serial No. 679,155.

To all whom it may concern:

Be it known that I, BENJAMIN KERR, a subject of the King of England, and resident of Sarnia, in the county of Lambton, in the Province of Ontario, in the Dominion of Canada, have invented certain new and useful Improvements in Automobile Cushions, of which the following is a specification.

This invention relates to improvements in cushions especially adapted for use on automobiles although not restricted to such use.

Briefly stated an important object of this invention is to provide a cushion consisting of a series of approximately air tight units having novel means whereby the air may be expelled when the cushion is compressed and slowly admitted when the compressing force is released, so as to prevent or overcome an objectionable rebound usually present in cushions.

A further object of the invention is to provide a cushion consisting of a plurality of separate and independent units held in an upright position by means of spiral loops which resist atmospheric pressure when the pressure within the cushion is reduced.

A further object is to provide a cushion which is of highly simplified construction, durable in use and cheap to manufacture.

Other objects and advantages will be apparent during the course of the following description.

In the accompanying drawings forming a part of this application and in which like numerals are employed to designate like parts throughout the same,

Figure 1 is a detail horizontal sectional view illustrating the improved cushion.

Figure 2 is a vertical transverse sectional view through the same,

Figure 3 is a detail bottom plan view of the invention.

In the drawing wherein for the purpose of illustration is shown a preferred embodiment of the invention, it will be seen that the improved cushion is made up of a series of more or less separate and independent units surrounded by coils 5. About nineteen (19) coiled springs 6 are arranged within each spiral body 5 and are enclosed within a flexible covering 7 of approximately air-tight material. The spirals 5 are also covered by the material 7.

A main covering 10 is extended over the several units and the additional springs 12 and is provided with a filling 13 of any

suitable material. The top of the inner covering 7 is arranged below the partition 14 which divides the cushion into an upper chamber for the reception of the filling 13 60 and a lower chamber for the reception of the several springs.

The bottom of each unit is provided with an outlet flap valve 16 which when the cushion is depressed will permit the air to escape, but will prevent the return of the air by way of the flap valve. Any air which enters the several chambers must do so by way of inlet openings 20, covered or partly covered by slide valves 21. By proper adjustment of the slide valves 21 the amount of air to enter the cushion may be regulated.

It will be seen that the several more or less separate and independent units are mounted on the bottom of the cushion and when the cushion is compressed a portion of the air will be expelled by way of the several valves 16. During the expansion of the springs the atmospheric pressure within the cushion is necessarily reduced and at this 80 time the spirals or loops 5 prevent the collapse of the several units as they withstand atmospheric pressure. Briefly stated, on the outside of the loops 5 and on top of the springs is a flexible covering approximately 85 air-tight. This makes each unit independent from all other springs or units. Outside the several units free atmospheric pressure is allowed and it is not necessary for the outer covering 10 to be air-tight. 90

With reference to the foregoing description, taken in connection with the accompanying drawings, it will be seen that the improved cushion will effectively absorb shocks and will reduce any rebound to a 95 minimum and the return of the cushion to normal position is gradual.

Having thus described the invention, what is claimed is:—

A cushion comprising a plurality of separate covering members having substantially air-tight chambers, separate groups of springs in said chambers, form sustaining coil springs for said covering members arranged in said chambers, and surrounding 105 said first named springs, said chambers being provided with one-way air outlet valves for the discharge of air when the cushion is compressed and with means to admit a variable volume of air on the expansion of the 110 cushion.

BENJAMIN KERR.
